CLAIM

The ornamental design for a food tray support, as shown and described.

DESCRIPTION

FIG. 1 is a top, front perspective view of a food tray support showing a first embodiment of my new design;

FIG. 2 is a bottom, back perspective view thereof;

FIG. 3 is a front elevational view thereof;

FIG. 4 is a back elevational view thereof;

FIG. 5 is a top plan view thereof; and,

FIG. 6 is a bottom plan view thereof.

FIG. 7 is a top, front perspective view of a food tray support showing a second embodiment of my new design;

FIG. 8 is a bottom, back perspective view thereof;

FIG. 9 is a front elevational view thereof;

FIG. 10 is a back elevational view thereof;

FIG. 11 is a top plan view thereof; and,

FIG. 12 is a bottom plan view thereof.

The broken lines shown in FIG. 2 are for illustrative purposes only and form no part of the claimed design.
